UNITED STATES PATENT OFFICE.

OSCAR GASSETT, OF BOSTON, MASSACHUSETTS.

MOTOR-PRESSURE GENERATOR.

SPECIFICATION forming part of Letters Patent No. 324,828, dated August 25, 1885.

Application filed October 13, 1884. (No model.)

To all whom it may concern:

Be it known that I, OSCAR GASSETT, of Boston, county of Suffolk, State of Massachusetts, have invented an Improvement in Motor-Pressure Generators, of which the following description, in connection with the accompanying drawing, is a specification, like letters on the drawing representing like parts.

My invention relates to an apparatus for generating fluid-pressure which may be employed in actuating mechanical motors or engines.

The invention consists, essentially, in apparatus for the combustion, in a confined space or chamber, of a combustible vapor or gas, the gases or heated products of combustion from which may be employed to actuate by their pressure or expansion an engine or motor of any suitable or usual construction.

The invention is embodied in an apparatus consisting, essentially, of a strong tight chamber, shown as tubular or cylindrical in shape, and a second closed chamber, shown as contained within the main chamber, the second or internal chamber, while the apparatus is in operation, being exposed to the action of a flame, by which it is heated to a high temperature. The said internal chamber is supplied with water, which is converted into steam therein, and the steam is employed in connection with a reservoir containing a combustible liquid—such, for instance, as the usual hydrocarbon compounds—to produce a jet of inflammable gas or vapor, which is ignited and produces a flame, by which the said chamber is heated to generate the steam. Sufficient air, preferably also heated by the flame, is supplied to support combustion, and the combined heated gases or products derived from the combustion of the hydrocarbon liquid with steam and air may be employed to actuate a mechanical motor or to perform work by their pressure and expansion.

Appliances are provided for producing steam in order to start the flame, and also for igniting the said flame when the apparatus is to be set in operation.

The drawing shows in longitudinal section an apparatus for generating gases under pressure embodying this invention. The heated

and expanded gases are generated in a main chamber or reservoir, *a*, which may be of any suitable size and shape. A steam-generating chamber, *b*, of cast or malleable iron, is shown as contained within the main chamber, and when the apparatus is in operation will contain steam under high pressure, generated as hereinafter described, and the said steam is conveyed therefrom through a pipe, *c*, to a nozzle or injector apparatus, *d*, from which it issues with great velocity and operates in the well-known manner to reduce the pressure in a pipe, *e*, communicating with a reservoir, *f*, containing oil or other hydrocarbon fluid, which, when combined with steam and air, produces a combustible gas or vapor. The flow of combustible liquid through the pipe *e* is controlled by a cock or valve, *g*, so that the proper amount may be combined with the issuing jet of steam, producing a combustible compound, which, when ignited, will burn with a flame that acts upon the internal chamber, *b*, heating it sufficiently to maintain the generation of steam therein as long as a sufficient supply of water is kept up. Air is admitted to the nozzle *d* in sufficient quantities to support combustion of the gaseous jet issuing from the nozzle *d* through a pipe, *h*, the said air being forced in under pressure, if necessary. The pipe *h*, preferably, is also exposed to the action of the flame, as shown, so that it combines with the inflammable gas or vapor in a highly-heated condition. More air may be admitted through an opening, *i*, if necessary, the amount being controlled by a suitable register.

In order to provide steam in the chamber *b* for producing the jet at first, before the flame has heated the chamber *b*, an auxiliary steam-generator, *k*, is connected with the said chamber *b* by pipes *m* and *n*, the latter controlled by a suitable valve, *o*, the said auxiliary generator *k* being heated in any suitable manner, as by the flame of a lamp, or alcohol contained in a saucer or chafing-dish, *k'*, for small apparatus, until steam is generated therein at sufficient pressure, when the said steam will flow through the pipe *m* to the chamber *b* and pipe *c*, when it will produce the combustible jet, as before described. The said jet thus produced

may be ignited in any suitable manner. As shown in this instance, the igniting device consists of a loop, n^5 , of fine platinum wire mounted on a spindle, p^5 , provided with a 5 suitable handle, p^6 , by which it may be turned from the outside of the chamber a , the said loop p^6 being connected in circuit with a suitable battery or generator of electricity, B. When the flame has been burning for a short 10 time, the chamber b will be sufficiently heated for the generation of steam therein, after which the heat may be removed from the chamber k and the valve o opened, admitting water to the chamber b in sufficient quantities to maintain 15 the jet in constant operation. The pressure in the chambers b and k is equalized by the steam passing through the pipe m to the upper portion of the chamber k , so that the water will flow to the chamber b by gravitation, its 20 amount being regulated by the valve o . The flame burning at d produces gases at a very high temperature, which, when confined, as in the chamber a , are under sufficient pressure to actuate a motor, the said gases being con- 25 veied from the reservoir a to the said motor, where they expand, and, in parting with their heat, produce mechanical work. But a very small amount of steam is required to produce the proper jet at the nozzle d , and as more 30 steam may be generated in the chamber b , the surplus may be discharged through a pipe, p , terminating in a nozzle within a concentric nozzle, r , connected with a partition, t , in the chamber a , so that the jet of steam issuing from 35 the pipe p will tend to force the gases from the side of the partition t , where they are generated, into the portion a' of the chamber in advance of the said partition, where the pressure will be greater, and from which the 40 mingled steam and gas may be taken to supply the engine. A check-valve, t' , in the partition t permits the gases to flow into the portion a' of the chamber when no steam is issuing from the pipe p , so that the pressure is 45 nearly equal on both sides of the partition. When the chamber k is nearly emptied of water, an additional supply may be introduced without interrupting the feed to the chamber b by means of a chamber, k' , the lower portion 50 of which is connected with the chamber k by a pipe, n' , containing a cock, n^2 . The upper portion of the chamber k' is connected by a pipe, m' , containing a cock, m^2 , with the pipe m , communicating with the steam-chamber b 55 and upper part of the chamber k . When the cocks n^2 m^2 are closed, the chamber k' is cut off from the chambers k and b , so that the said chamber k' may be readily filled. Then, by closing the inlet to the chamber k' and opening 60 the cocks m' n^2 , the steam-pressure in the chambers k and k' will be equal, and the water will flow by gravitation from the chamber k' into the chamber k . The chamber a' may be provided with an outlet-pipe, u , controlled by 65 a valve, u' , which may be opened when the apparatus is being first set in operation, in

order to afford a ready escape for the products of combustion, so that there will be no pressure to resist the entrance of air and combustible liquid until the combustion is thoroughly 70 under way. A removable plate or bonnet, t' , may be provided for affording access to the nozzle d , and the said plate may be removed for the purpose of igniting the flame, if desired. A block, w , of refractory material will pref- 75 erably be placed in the path of the flame issuing from the nozzle d , the said block becoming very highly heated, and thus retaining sufficient heat to ignite the gaseous jet after a momentary interruption in the flow of the gas, in 80 case one should occur. The block w is provided with a hole for the passage of the flame through it.

I claim—

1. In an apparatus for generating gases under pressure, the combination of the following elements, namely: the main casing or chamber for containing the gaseous products, a steam-generating chamber, a reservoir for combustible fluid, and a nozzle communicating with the 90 steam-generating chamber, the jet of steam from which nozzle acts on the fluid supplied from the reservoir, whereby in the operation of the apparatus a jet of combustible gas or vapor is produced, the flame of which acts upon 95 the steam-generating chamber, substantially as described.

2. In an apparatus for generating gases under pressure, the combination of an outer casing for containing the gaseous products, a 100 steam-generating chamber, and water-reservoir communicating with the latter, with a reservoir for combustible fluid and a nozzle communicating with the steam-generating chamber and with the reservoir for combustible material, whereby when steam is generated in the generating-chamber it produces a combustible jet, the flame of which, when ignited, acts upon the said generating-chamber, substantially as described.

3. The combination of the outer chamber provided with an air-inlet, an internal steam-chamber, and the water-reservoir communicating with the latter, with a reservoir for combustible fluid, a nozzle communicating with 115 the internal chamber, and a duct conveying the combustible fluid into the outer chamber, substantially as described.

4. The main and internal chambers for combustible fluid, combined with a nozzle communicating with the said internal chamber and reservoir and an igniting device capable of operation from the exterior of the main chamber, substantially as described.

5. The main chamber and steam-generating 125 chamber heated by a flame in the main chamber, combined with an outlet-pipe from the said steam-generating chamber and a co-operating nozzle, whereby a jet of steam is caused to act upon the gaseous products, substantially 130 as described.

6. The main chamber and steam-generating

chamber, combined with a reservoir for combustible fluid, a nozzle communicating with the said steam generating chamber, and an air-supplying duct exposed to the action of a jet 5 or flame issuing from the said nozzle, substantially as described.

In testimony whereof I have signed my name

to this specification in the presence of two subscribing witnesses.

OSCAR GASSETT.
